UNITED STATES PATENT OFFICE.

LOFTUS GEORGE COADE, OF BIRMINGHAM, ENGLAND.

SEWING-MACHINE.

1,225,772.

Specification of Letters Patent.

Patented May 15, 1917.

Application filed November 27, 1914. Serial No. 874,297.

To all whom it may concern:

Be it known that I, LOFTUS GEORGE COADE, subject of the King of Great Britain, residing at No. 448 Birchfield road, Perry Barr, Birmingham, England, have invented certain new and useful Improvements in Sewing-Machines, of which the following is a specification.

This invention relates to improvements in sewing machines the object of which is to invoke as a mechanical relay a portion of the driving energy automatically to effect the stopping of the machine when the fabric is depleted or fed to the machine in a deviated position.

The invention will be described by reference to the accompanying drawings.

In these drawings:—

Figure 1 is a front elevation showing the device for effecting the connection of the machine with the source of driving-energy and the means for effecting the disconnection therefrom and for stopping the machine.

Fig. 2 is a sectional elevation at right angles to Fig. 1 and on a larger scale showing the means for automatically stopping the machine in the event of the supply of fabric for the sewing operation becoming depleted, which stopping device is adapted to come into operation also if and when the fabric is conveyed to the machine with its borders laterally deviated from the correct line of progress to an undue amount.

A is the sewing-machine provided with a pulley a which is strap-driven from a source of power through the medium of a set of coaxially mounted pulleys, of which a^1 is directly connected to a by a strap; a^1 being frictionally driven by the side pressure thereon of a compound-pulley a^2 which is itself driven by another strap which embraces any one of a set of grooves formed thereon. The frictional drive is transmitted by a leather ring a^3 when a pin carried on the end of the arm a^4 of a pivoted-lever is forced into contact with a^2 . The arm a^4 is formed integrally with an arm a^5 to which force is applied to perform the clutching operation and also with an arm a^6 on which is carried a brake-piece a^7 which, on being forced into the groove of the pulley a^1 , stops the sewing-machine.

Between the end of the arm a^6 and a fixed bracket a^8 is interposed a spring a^9 . When, to effect the clutching operation, a down-

ward pressure is applied to the arm a^5 , the spring a^9 will be compressed and the brake released and when the pressure on the arm a^5 is removed, energy stored in the spring a^9 will be rendered available to unclutch the pulleys a^1 a^2 and apply a braking force to the pulley a^1 .

The above-described, well-known, clutching and braking contrivance is rendered available to serve the purpose of the present invention by the combination therewith of a tripping-device comprising a pivoted-lever B of which one arm b is provided with a roller and its extremity so arranged that when the arm b is placed at right angles to the surface of the arm a^5 the latter will be thrust into the clutching position, the arm b being then in such a state of unstable equilibrium that a small displacement thereof will release the before-mentioned spring a^9 and enable it to operate as a mechanical-relay to disconnect and arrest the motion of the sewing-machine. The lever B is shown provided with two other arms viz. a loaded arm b^1 and another arm b^2 , which is, with permissible lost-motion, connected to a rod d whereby the compound-lever B will be required to undergo a displacement as a consequence of imperfection in the supply of fabric to the sewing-machine.

The fabric H is conducted over a pair of parallel bars h^1 h^1 , the extremities of which are carried on levers h^2 , keyed to a shaft h^3 , to which other levers are also keyed as will be presently described. Resting on one or each of the two borders of the portion of the fabric lying between the bars h^1 h^1 is a feeler h , which by a link h^4 supports a partially counterbalanced lever h^5 , which is pivotally mounted on the extremity of a lever h^6 which also is keyed to the shaft h^3 . The lever h^5 constitutes, for the present purpose, the passive engaging-element of this invention, and to enable it to perform its desired function it is, at its free extremity, formed with a claw h^7 adapted to engage with a continuously rotating claw h^8 constituting the active engaging-element. The claw h^8 is keyed on a shaft h^{12} continuously rotated by a pulley h^{13} and belt h^{14} .

If, on account of the depletion of the fabric or the lateral displacement of its border to such a degree that either of the feelers h fail to receive the support normally due to the pressure of the fabric progressing between it and the bars h^1 h^1 , the claw h^7

2
of the lever h^5 will drop and interpose itself in the path of the claw h^8 , whereby a force will be exerted angularly to displace the shaft h^3 . To the shaft h^3 is keyed a lever 5 h^9 and this by a link h^{10} and a bell-crank h^{11} , is interconnected with the before-mentioned rod d of Fig. 1 whereby, as previously described, the machine will be stopped.

The angular displacement of the shaft h^3 10 will cause the several components of the above-described mechanism to undergo a change of position as indicated in dotted lines.

I claim:

- 15 1. In a sewing-machine, a clutch driving said machine, tripping means for retaining said clutch in engagement with said machine, supports beneath the fabric led through said machine, a lever connected to said tripping means, a claw on said lever, a 20 feeler resting on the border of said fabric between said supports and connected to said claw lever and a moving claw adjacent to said claw.
- 25 2. In a sewing-machine, a clutch driving said machine, tripping means for retaining said clutch in engagement with said machine, supports beneath the fabric led through said machine, a lever connected to 30 said tripping means, a claw on said lever, a feeler resting on the border of said fabric between said supports and connected to said

claw lever and a rotating claw adjacent to said claw.

3. In a sewing-machine, a clutch driving 35 said machine, tripping means for retaining said clutch in engagement with said machine, pivoted supports beneath the fabric led through said machine, a lever connected to said tripping means and to said pivoted 40 supports, a claw on said lever, a feeler resting on the border of said fabric between said supports and connected to said claw lever and a rotating claw adjacent to said claw.

4. In a sewing-machine, a clutch driving 45 said machine, tripping means for retaining said clutch in engagement with said machine, a shaft connected to said tripping means, levers secured to said shaft, bars extending between said levers beneath the 50 fabric led through said machine, another lever secured to said shaft, a lever pivoted to said last-mentioned lever, a feeler resting on the border of said fabric between said 55 bars and connected to said pivoted lever, a claw on said pivoted lever and a rotating claw adjacent to said claw.

In testimony whereof I affix my signature in presence of two witnesses.

LOFTUS GEORGE COADE.
